(57) **CLAIM**

The ornamental design for an integrated multi-function remote control, as shown and described.

DESCRIPTION

FIG. 1 is a front elevational view of an integrated multi-function remote control showing my new design;

FIG. 2 is a top plan view thereof;

FIG. 3 is a bottom plan view thereof;

FIG. 4 is a right side elevational view thereof;

FIG. 5 is a rear elevational view thereof; and,

FIG. 6 is a left side elevational view thereof.

The broken line showing of letters in FIGS. 4 and 5 is for illustrative purposes only and forms no part of the claimed design.
